UNITED STATES PATENT OFFICE.

HAROLD R. BIRDSSELL, OF TOLEDO, OHIO.

CALENDAR.

1,107,251.

Specification of Letters Patent. Patented Aug. 18, 1914.

Application filed April 9, 1914. Serial No. 830,743.

To all whom it may concern:

Be it known that I, HAROLD R. BIRDSSELL, a citizen of the United States, and a resident of Toledo, in the county of Lucas and 5 State of Ohio, have invented a certain new and useful Calendar; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates particularly to calendars of the type adapted to be used repeatedly, year after year, but is not restricted to such use, as it may be used in any connection for which it is adapted or 20 appropriate.

The primary object of my invention is the provision of simple and efficient means for supporting or suspending the several cards of a calendar in exposed position, one 25 in front of another, in proper order, and to permit such cards to be successively moved to a different position, without turning, whereby to expose the next card in order.

30 It is also the object of my invention to provide means for holding a plurality of cards in either one of two positions and for guiding the sliding movements of the cards in proper order, from one position to the 35 other, each card, as it is shifted from one pack or position to the other, moving from the front of one pack to the rear of the other, or vice versa; or in other words, each card, when shifted, stands in reverse position 40 with respect to the pack to which shifted to the position which it bore with respect to the other pack.

The invention is fully described in the 45 following specification, and while, in its broader aspect, it is capable of embodiment in numerous forms, a preferred embodiment thereof is illustrated in the accompanying drawings, in which,—

Figure 1 is a perspective view of a calendar embodying my invention. Fig. 2 is 50 an enlarged vertical section thereof with the cards partly in full, and Fig. 3 is a perspective view of a portion of the device illustrating the manner in which the cards 55 of one pack are moved to the rear of the

cards of the other pack when being shifted from one position to another.

Referring to the drawings, 1 designates a back plate or body member, which may be of sheet metal or other suitable material, 60 and 2 a plurality of members which are secured to said plate and serve to suspend a plurality of cards 3 in either of two positions relative to the plate and to guide the movements of the cards from one to the 65 other of such positions.

The plate 1 is intended to be vertically suspended and the members 2 are disposed lengthwise or vertically thereof, being secured to the plate at their upper and lower 70 ends in any suitable manner, as hereinafter described. The members 2 are preferably made of spring strap metal, and each is provided at or adjacent to its upper end with a loop 4, which extends outwardly 75 from the plate and has its leg portions vertically spaced, with the lower leg 4^a thereof forming a substantially horizontal ledge for supporting the cards 3 in raised position with relation to the plate. The ledge 80 or lower leg portion 4^a of the loop 4 has its free end portion in yielding contact with the plate 1 and thence extends downward in preferably slightly outwardly inclined relation to the plate 1, as shown at 5, the 85 incline being preferably increased near the lower end of the member, as at 6, and finally terminating in the abrupt inwardly turned ledge portion 7. This ledge portion serves to support the cards 3 in their lowered position.

The lower end of each guide member 2 is removably secured to the plate 1, in the present instance, by projecting the end portion 8 of the member through a registering opening 9 in the plate and shouldering such end portion within the opening, as shown. The upper end of the member is removably secured to the plate, in the present instance, by providing the upper leg portion 4^b of the 95 loop 4 at its inner or free end with an upstanding lip 10 which is projected through a registering opening 11 in the plate and engages the rear side of the plate at the upper end of the opening. The opening 11 is of 100 substantially the same depth as the lip 10 to enable the lip to be projected therethrough when the legs 4^a and 4^b of the loop are relatively compressed for such purpose, the spring action of the loop normally retaining 110

the legs in outwardly sprung relation, as shown in Fig. 2.

The cards 3, in the present instance, are shown as being arranged in three sets *a*, *b* and *c*, disposed side by side, the cards in the set *a* preferably being twelve in number, and each bearing the name of a different month, the cards in the set *b* preferably being thirty-one in number, and bearing in consecutive order numbers representing the days of the month, one being provided on each card, and the cards in the set *c*, preferably being seven in number, and each bearing the name of a different day of the week. The cards of the set *b*, in the present instance, are carried by two guide members, while each of the other sets *a* and *c*, being of less width than the cards *b*, is carried by a single guide member 2. It will be understood, however, that this arrangement is not important, as the number of guide members employed for each set of cards depends largely upon the width of the cards. The upper end of each card 3 is provided with an opening or openings 12 through which the respective guide members 2 loosely project, as shown.

In the device illustrated herein the lower position of the cards is the display position thereof, and when it is desired to shift the outer card in any set to display the card next in order, the outer card is moved upward on the respective guide member or members 2, as the case may be, to its upper suspending position on the ledge 4^a of the member. The upper end of the guide portion 5—6, which connects the card suspending ledges 4^a and 7, has a yielding spring pressure against the plate 1 to prevent a card from accidentally moving downward from the ledge 4^a. If the shifted card of a set is not the first one in order the guide member 2 will guide it to the rear of the cards previously shifted so that the shifted card stands in reverse position with respect to the pack to which shifted to the position which it bore with respect to the cards from which it was shifted.

When it is desired to return the cards from their upper to their lower position the upper ends of the guide members are disengaged from the plate 1 so as to release the pressure of the inner end of the ledge 4^a against the plate to facilitate a lowering of the cards.

In order that the cards may be hidden from view when shifted from display position a box or cover member 13, having an open bottom, is secured to the upper portion 60 of the plate 1 in position to cover the cards when in their upper positions, as shown. The box member 13 is preferably hinged to the plate 1, as at 14, to facilitate access to the cards when in their upper position. The outer side of the box 13 provides a plain sur-

face for any suitable advertising or other display matter.

It will be understood that while I have particularly illustrated my invention as applied to a calendar, it is not restricted to such use, as it may be used in any connection for which it may be adapted or appropriate, and that the number of the cards of a set may be varied to suit the demands of the particular use. It is also to be understood that the invention is not limited to any specific construction or arrangement of the parts, as numerous modifications can be made without departing from the spirit thereof.

Having thus described my invention, what I claim as new, and desire to secure by Letters Patent, is,—

1. The combination with relatively shiftable card-like members each having an opening therein, of means projected through the openings of the members and having vertically spaced member suspending portions, and a guide portion connecting the outer end of one suspending portion to the inner end of the other.

2. The combination with a plurality of card-like members having openings therein, of an upstanding part extending through the openings in said members and having vertically spaced ledges forming supports for said members when in raised or lowered positions and having guide portions connecting the inner end of one to the outer end of the other of said ledges.

3. In combination, a holder part, a member suspending and guiding means carried by said part and having vertically spaced member suspending parts and a portion connecting the inner end of one to the outer end of the other of said suspending parts, and a set of relatively shiftable members carried by said means and shiftable in upright position from one to the other of said ledges.

4. In combination, a body part, a vertically disposed card guiding and suspending member carried by said part, said member having vertically spaced card suspending ledges and a guide portion connecting the inner end of one to the outer end of the other of said ledges and having one ledge in yielding contact at its inner end with said body part, and a set of relatively shiftable elements engaged by said member and shiftable in upright position from one to the other of the suspending ledges thereof.

5. In combination, a body part, a spring metal member carried by said part and having its opposite ends connected to said part with its upper end in removable connection therewith, said member being provided adjacent to its upper end with an outwardly looped portion, the lower leg of which portion forms a supporting ledge and has yielding contact at its inner end with said

body part, thence extending downward and outward from the body part and having a reëntrant ledge adjacent to its lower end, and a set of cards each having an opening 5 through which the member is projected, said cards being shiftable in upright position from one ledge to the other and held in suspended position by either ledge.

In testimony whereof, I have hereunto signed my name to this specification in the 10 presence of two subscribing witnesses.

HAROLD R. BIRDSELL.
